FIG. 1.

FIG. 12.

FIG. II.

INVENTOR:

THOMAS F. BYRON

BY Saywell and Webster
ATTORNEYS

UNITED STATES PATENT OFFICE

2,272,656

CURTAIN

Thomas F. Byron, Cleveland, Ohio

Application July 6, 1940, Serial No. 344,240

6 Claims. (Cl. 156—33)

The invention relates to curtains and particularly to that class of curtains well known as window curtains and made of sheer, light weight materials, such as marquisette net, lace, Swiss voile, etc. The improvements set forth herein are designed to provide for the perpendicular even hanging of curtains of the character noted.

Light weight curtains made of sheer materials have a tendency to sag when hung to the windows. There are several causes for this tendency. One of the principal causes arises from the fact that the curtains are provided with side hems. At the hemmed line or in the line of the hem seam the extra curtain thicknesses folded to form the stitching line hold the curtains more rigidly than at other parts of the curtain body so that the middle part of the curtain has a sagging appearance and the curtain sides pull up. As a result the side edges do not hang perpendicularly straight thus causing the curtains to present an unsightly appearance. Also, in most cases, curtains of this character are dependently supported from and shirred to a rod at the top, and with considerable fullness, which crowds the curtain width at the top creating a curtain flare at the bottom so that the curtains do not hang straight on the outer edges. Furthermore, this flare causes a pair of curtains to lap each other at their inner edges at the bottom, the entire effect being a very uneven hanging and producing a very unsightly appearance.

The improvements presented herein are designed to overcome the aforementioned disadvantages.

The annexed drawing and the following description set forth in detail certain means illustrating the invention, such disclosed means constituting, however, only a few of the various forms in which the principle of the invention may be embodied.

In said annexed drawing:

Figure 1 is an elevation of a pair of the improved curtains as they would appear in hanging position from the inside of the room in which they are used;

Figure 2 is a rear elevation, Figure 3 a bottom edge view, and Figure 4 a diametrical section, of a plummet-like attachment forming part of the improved curtain structure;

Figure 5 is a front elevation, and Figure 6 a diametrical section, of a second form of attachment, Figure 6 also indicating in dotted lines the inward bending of the prongs of a certain fastening portion of the attachment, after the attachment has been placed in position upon the curtain

body, so as to prevent the ends of the prongs from catching in and disfiguring wall-paper, window casings, etc.;

Figure 7 is a rear elevation, Figure 8 a diametrical section, Figure 9 a diametrical section at right angles to the section of Figure 8, and Figure 10 a front elevation, of a third form of attachment, Figure 8 also indicating in dotted lines the outward bending of the prongs of a certain fastening portion of the attachment, after the attachment has been placed in position upon the curtain body, so as to prevent the ends of the prongs from catching in and disfiguring wall-paper, window casings, etc.;

Figure 11 is a fragmentary vertical section along a seam line at the lower end of the improved curtain, showing the attachment illustrated in Figures 7-10 incorporated therein; and

Figure 12 is a fragmentary outside elevation of a lower corner of the curtain shown in Figure 11, i. e., an elevation from outside the room.

Referring to the annexed drawing in which the same parts are indicated by the same several numbers in the different views, Figure 1 shows a pair of the improved curtains 1 hanging in proper relative positions, the same being suspended from the top upon a rod 10 intersecting curtain pockets 18. As is quite usual in the hanging of such curtains, they are arranged with considerable fullness, as clearly indicated in Figure 1.

The curtains 1 are provided with side hems 2 having the stitch or seam lines 3. Also, they are formed with bottom hems 4 having the stitch or seam lines 5. The hems are formed so that the bottom hems 4 are open-ended pockets, i. e., the edges 6 are open. The curtain bodies are first turned and stitched to form the side hem 2 and then the bottom is turned and stitched to form the bottom hem 4. Thus, the walls of the curtain bottom corner portions defined by the seam lines 3 and 5 are of double thickness. Also, at the curtain top there is a hem 15 having two spaced seam lines 16 and 17 whereby the rod pocket 18 is formed in the hem 15.

In order to secure the even perpendicular hanging of the curtains 1, a result which normally is not attained because of the tendency of the curtains to flare out at the bottom, due to the crowded width at the top, and due to their tendency to pull up at the side edges 7 because of the holding effect of the increased thickness of the material created by the seams 3, plummet-like attachments are secured to the curtains 1 adjacent the bottom ends thereof, preferably incorporated within the thicknesses of curtain mate-

rial forming the bottom hem 4, and most preferably along the seam lines 3.

These plummet-like attachments which are of a distinctively weighted character may be of different formations having a body member of suitable weight for the purpose desired and a prong-like securing member by which the weighted body may be detachably secured to the curtain body, the weighted body also preferably being of a formation such that, when the weight is in position on the curtain material, the prong of the weighted body may be so positioned as not to extend laterally outwardly from the weighted body, whereby the prong is prevented from catching in and scratching or otherwise disfiguring other adjacent objects, such as the building wall, window jamb, wall-paper, etc.

Three forms of the plummet-like attachment forming part of the improved curtain are shown in the accompanying drawing. All of these forms have a button-like heavy body, such as a lead body suitably surface finished and of a formation such that a pin-like member, formed therewith or suitable for incorporation therewith and used for detachably securing the body to the curtain material, can be positioned within the confines of the weighted body when the latter is in position upon the curtain.

Referring particularly to the form of weighted attachment shown in Figures 2, 3, and 4, a heavy disk-like body 8 is formed in its rear face with a diametrical surface recess 8' within which is convergently positioned a flexible pin 9 securely seated by an angular end portion 9' in and adjacent the edge of the body 8, so as to form a detachably fastenable button-like weight which is secured to the bottom of the curtain 1 and, preferably, between the thicknesses 4' and 4² of the bottom hem 4 thereof; and also, preferably, along the line of the seam 3 so that the weight can draw on the seam 3 which does not sag to the extent of the other parts of the curtain. It will be noted in Figure 4 that the front part of the angular end portion 9' of the pin 9 is seated in a recess 8² formed in the front face of the button body 8 so that this part of the angular pin portion 9' lies flush with the said face of the body 8. The convergent formation of the pin 9 provides for a secure holding of the fastener in the hem 4 against the outside hem thickness 4² which is pressed against the disk-like body 8, and also effects the positioning of the sharp point of the pin 9 between the hem thickness 4' and 4². Thus the sharp point of the pin 9 is prevented from scratching or defacing adjacent walls or furnishings. The weighted attachment is positioned in or removed from the hem 4 through the open pocket edge 6.

Referring particularly to the form of weighted attachment shown in Figures 5 and 6, a concavo-convex heavy body 11, of saucer-like formation, is provided with a surface recess 11' in the rear concave face thereof which is intersected by the prongs of a flexible staple-like fastener 12 formed of suitable wire and passed through and seated in the weighted body 11 and having its intermediate portion 12' seated in a recess 11² formed in the convex front face of the body 11. When the weighted fastener 11 has been positioned between the thicknesses 4' and 4² of the hem 4 with the prongs of the fastener 12 extending outwardly through the thickness 4², the prongs can be turned inwardly across each other and disposed in the recess 11', as shown in Figure 6,

whereby the sharp points of the prongs are prevented from scratching or defacing adjacent walls or furnishings.

Referring to the form of weighted attachment shown in Figures 7-12, a heavy body 13 of disk-like formation is formed in its rear face with a pair of spaced radial recesses 13² separated by a central recess 13³, the recesses 13² being defined by three-sided beveled formations 13', as clearly shown in Figures 7, 8, and 9. The sides of the beveled formation 13' do not extend quite so high as the height of the normal part of the body 13 so that there is formed at the top of the central or intermediate side of each of the beveled formations 13' a sharp edge 13⁵ whose purpose will be hereinafter fully mentioned. Passed through the body 13 is a flexible staple-like fastener 14 having sharp pointed end portions 14' and whose intermediate portion 14² is seated in a recess 13⁴ formed in the front face of the body 13. When the described weighted attachment is passed through the open pocket end 6 of the hem 4 between the front thickness 4' and the rear thickness 4², as shown in Figure 11, and the weighted attachment secured in the hem 4 along the line of the seam 3, as shown in Figure 12, the plane face of the body 13 being presented to the face of the front hem thickness 4', as shown in Figure 11, and the sharp prong portions 14' of the staple-like fastener 14 being passed through the outside hem thickness 4², the prong portions 14' can be bent outwardly over the sharp edges 13⁵ formed by the three-sided beveled parts 13' into the recesses 13², all as clearly shown in Figure 11. Thereby the sharp prongs 14' are depressed below the surrounding face of the curtain and thus prevented from scratching or defacing adjoining wall or furnishing elements. It will be clearly noted from Figure 11 that the portions of the hem thickness 4² adjacently laterally of the prongs 14' hang in their normal position as indicated by dotted lines, the prongs 14' being substantially enveloped by the hem thickness 4².

The several forms of weighted attachments are so securable to the hem 4 that they are readily and conveniently attached and, when it is desired to launder the curtains 1, they can readily and conveniently be detached therefrom and then again placed in position thereon when it is desired to rehang the curtains 1.

The weight of the attachment can be such as is suitable for the purpose, according to the tendency of the particular curtain material to sag, or the nature of the particular curtain hanging to cause sagging; and the attachment can be formed in various shapes and designs.

What I claim is:

1. A plummet-like attachment for curtains comprising a weighted body having a spring-pin member for detachably securing the body to a curtain, the body having a surface recess within which the pin member is disposed in securing position.

2. A plummet-like attachment for curtains comprising a weighted button-like body formed with an aperture therethrough and with a surface recess, and an end-pointed wire having a portion seated in said aperture and whose pointed end is bendable for disposition in said recess.

3. A plummet-like attachment for curtains comprising a weighted button-like body formed with an aperture therethrough and with a plurality of spaced surface recesses, said aperture opening into some of said recesses, and an end-

pointed flexible wire having a portion seated in said aperture and having its pointed end disposed adjacently the body material between contiguous recesses for bending thereover to position said end in securing position in a body recess.

4. A non-sagging curtain comprising a sheer curtain body formed for dependent supporting adjacent one end and having side hems, the opposite curtain end being formed with an upturned hem forming front and back hem walls, the pocket formed between said walls being open-ended, and detachable weights for effecting the perpendicular relatively even hanging of all parallel lengthwise sections of the curtain secured to said curtain rod within said pocket.

5. A non-sagging curtain comprising a sheer curtain body formed for dependent supporting adjacent one end and having side hems, the op-

posite curtain end including the adjacent side hem portions being formed with an up-turned hem forming front and back hem walls of multiple plies, the pockets formed between said walls being open-ended, and detachable weights for effecting the perpendicular relatively even hanging of all parallel lengthwise sections of the curtain secured to said curtain body within said pockets in alignment with the seams of the side hems.

6. A plummet-like attachment for curtains comprising a weighted body having a surface recess, a flexible fastening member incorporated with said body and adapted detachably to secure the body to a curtain, the fastening member being tensioned to seat itself normally in said recess.
